UNITED STATES PATENT OFFICE.

SETH F. KNIGHT, OF CHICAGO, ILLINOIS, AND ALMON E. NORRIS, OF BROOKLINE, MASSACHUSETTS, ASSIGNORS TO MEAD-MORRISON MANUFACTURING COMPANY, OF BOSTON, MASSACHUSETTS, A CORPORATION OF MAINE.

CAR DUMPER.

Application filed August 18, 1924. Serial No. 732,618.

This invention relates to a novel and improved car dumper of the rotating cradle type, and will be best understood by reference to the following description, when taken in connection with the accompanying drawings of one illustrative embodiment thereof, while its scope will be more particularly pointed out in the appended claims.

In the drawings:
 10 Fig. 1 is a side elevation of a car dumper embodying the invention;
 Fig. 2 is an end elevation of the same, as viewed from the right-hand side of Fig. 1, the hopper, however, being shown in vertical section;
 15 Fig. 3 is an end elevation on an enlarged scale, illustrating the cradle and the car clamping means, the latter being shown in the position which it occupies when in engagement with the car;

Figs. 4, 5, 6, 7 and 8, are diagrammatic views on a reduced scale, illustrating the operation of the dumper, Fig. 4 showing the parts in their normal or initial positions, 25 Figs. 5, 6 and 7, showing successive positions occupied by the parts, and Fig. 8, the final or dumping position; and

Fig. 9 is an elevation on an enlarged scale, as viewed from the right-hand side of Fig. 2, illustrating the cable-tensioning weights, their guides, and the adjacent sheave wheels.

Referring to the drawings, and to the embodiment of the invention which is selected for exemplification, there is shown a car dumper comprising one or more, herein two, hoppers 10 (see Figs. 1 and 2), which in practice may be of molded concrete. The sides of these hoppers present convenient supports for a framework 11 for some of the operating mechanism hereinafter described. Within this framework is a car-receiving cradle 12, which is mounted to rotate about a longitudinal axis within the car-receiving space, as by providing the cradle with a plurality of wheels 13, encompassing the car-receiving space, and resting upon supporting wheels 14 (see Fig. 2)

arranged in pairs, the wheels of each pair being carried by equalizers 15, which are fulcrumed on pivots 16 on brackets 17, supported by the sides of the hoppers.

The cradle carries a car-track 18 (best shown in Fig. 3), which in the present example is mounted for transverse movement, and to this end, herein is mounted on a platen or platform 19, having wheels 20, resting on a transverse track 21. A car 22, indicated in dotted lines in Fig. 2, is placed in position in the cradle by being run onto the track 18. In the normal position, the car clears both sides of the cradle, but it may be caused to move laterally against an abutment 23 carried by the cradle, by virtue of a lateral movement of the car and the track, under the influence of gravity, assisted by means now to be described. One or more springs 24 (see Fig. 3) interposed between the platen and one or more fixed abutments 25 tend to urge the car and platen toward the left, as viewed in Fig. 3. This tendency, however, is normally resisted by appropriate means, herein one or more rods 26, which may be equipped with rollers 27, normally engaging an abutment presented by one side of the hopper. When, therefore, during the rotation of the cradle counterclockwise, as viewed in Fig. 3, the roll 27 recedes from the fixed abutment, the springs 24 assert themselves by urging the platen toward the left, with the assistance of gravitation due to the inclined position which the transverse trackway then assumes.

When, therefore, the car moves laterally, its side contacts with the abutment 23, where it remains until it has been dumped and returned toward its normal position, when re-engagement of the rollers 27 with the fixed abutments will cause the car and platen to be moved toward the right into the position represented in Figs. 2 and 3.

The car clamping means are now to be described, reference being had at first to Fig. 3. A car clamp 28, which normally occupies an upright position, as represented in

Fig. 2, is appropriately mounted for vertical and swinging movement by mounting the same on a pivot 29 carried by an appropriate carrier, herein a slide 30, which is guided by normally vertical guides 31 presented by the cradle. This carrier has an abutment 32, which, when the carrier is lowered sufficiently, rests upon the upper edge of the car, as represented in Fig. 3, thus 5 stopping the downward movement of the carrier, as well as serving as a part of the clamping means.

The clamp is controlled by a clamp-controlling cable 33, which as shown in Fig. 2 is 10 secured to the clamp, and leads in an upward direction over a sheave wheel 34, thence in a horizontal direction to and over a sheave wheel 35, thence in a downward direction over a sheave wheel 36, thence in an upward direction 15 over a sheave wheel 37 (see Fig. 9), whence it leads in a downward direction to and about a clamp-controlling, cable-winding drum 38. A weight 39, supported by the sheave wheel 36, serves to tension the cable. 20 The ascent of this weight is limited by a fixed stop 40 presented by the framework. When the drum 38 is rotated in the proper direction to pay out the cable, the clamp and its slides are permitted to descend until the 25 stop carried by the slide rests upon the top of the car, whereupon the weight 39 will descend from the stop 40 and the clamp will commence to swing about its pivot from the position shown in Fig. 2 to that which is 30 represented in Fig. 3.

The cradle rotating means will now be described, reference being had at first to Fig. 1. Each wheel 13 presents two grooves 41 for cradle rotating cables 42, each of which is 35 dead-ended at 43 on the cradle, and is provided with a turnbuckle 44 for adjustment of its tension. The ropes lead across each other (see Fig. 2), and are wound in opposite directions about a drum 45 (see Fig. 1). Each 40 of these drums is suitably rotated, as by being provided with a spur gear 46, which, as shown in Fig. 2, meshes with and is driven by a pinion 47 secured to a shaft 48, to which is also secured the clamp-controlling, cable-winding drum 38. By this means, the operations 45 of the cradle-rotating means and the car-clamping means are coordinated, and rotation of the cradle from its normal position is accompanied by engagement of the car-clamping means with the car. There is a 50 differential action between the cables 33 and 42,—that is to say, the cable 33 is paid out and wound in faster than the cable 42, as a result of which the clamp continues to rest upon and hold the car until, following the 55 dumping operation and during the restoration to the normal position, the ascent of the weight 39 is stopped by the stop 40, whereupon the shoulder 32 of the clamping means 60 rises out of engagement with the car.

Herein, the car-clamping means is rendered doubly effective by the use of a car-clamping cable 49 (see Fig. 2), which is dead-ended at 50 on the framework, and leads therefrom between a small sheave 70 wheel 51 and a large sheave wheel 52 carried by the clamp 28; thence over another sheave wheel 53 mounted on and concentric with the pivot 29, thence over a sheave wheel 54 carried by the car-receiving cradle, thence 75 horizontally over another sheave wheel 55 carried by said cradle, thence in an upward direction over a sheave wheel 56 mounted on the framework 11, thence horizontally over a second sheave wheel 57 80 on said framework, and finally in a downward direction. A weight 58, secured to the free end of the cable serves to maintain the cable properly tensioned. It will be observed that this cable partially encompasses 85 the car. When, therefore, the cradle starts to rotate from its normal position, represented in Fig. 4, after a short angular movement of the cradle, the car-clamping cable starts to wrap about the car, so to speak. 90 At first, the cable, by engagement with the sheave wheels 52 and 53, swings the car-clamp 28 through the successive positions represented in Figs. 5 and 6 to that which is shown in Fig. 7, wherein it is clamped 95 against the car top.

During the early part of these movements, the cable is assisted by the action of gravity (see Figs. 5 and 6), but before the position shown in Fig. 7 is reached, the force applied 100 to the clamp is furnished jointly by the cables 49 and 33, and from then on to the dumping position illustrated in Fig. 8. Toward the end of this movement (i. e.: after reaching the position shown in Fig. 7), 105 the car-clamping cable leaves the sheave wheel 55, and does not reengage the same until the cradle, during its reverse rotation, reaches the same point.

The general operation should be evident 110 without further description, but will be reviewed briefly. Assuming the cradle to be in its normal position, the loaded car is run into place, and power is applied to the shaft 48 on the driving mechanism. The cradle 115 starts to rotate contraclockwise, as viewed in Fig. 4, and the clamp and its carrier start to descend. The car moves laterally into engagement with the stop, which arrests its movement, and the clamp then descends 120 upon the car, assisted by the clamping cable, which becomes wrapped about the clamp and car, until finally the dumping position shown in Fig. 8 is reached, thus discharging the contents of the car. At this point, the direction of rotation of the driving mechanism is reversed, and the car is restored to its normal position by a reversal of the foregoing operations, after which the empty car is removed from the cradle. 125 130

Having thus described one embodiment of our invention, but without limiting ourselves thereto, what we claim and desire by Letters Patent to secure is:

5. In a car dumper, the combination of a track for the car wheels, a cradle presenting a support on which said track is mounted for transverse movement, an abutment carried by said cradle adapted to limit transverse movement of said car and track in one direction, yielding means urging said car and track in such direction, means normally resisting movement of said car and track in such direction, but adapted to permit such movement when said support moves in the opposite direction, cradle supporting means on which said cradle is mounted for rotation about an axis within the space occupied by said car, cradle rotating means, a vertically movable clamp carrier carried by said cradle and carrying an abutment movable vertically into and out of engagement with the top of said car, a car clamp pivoted to said carrier and adapted to swing into and out of engagement with the top of the car, a clamp-controlling cable secured to said clamp and sustaining said clamp and its carrier, a clamp-controlling, cable-winding drum, clamp-controlling cable tensioning means, a car-encompassing, clamp-holding cable disposed at least part way about the car-receiving space, and clamp-holding cable tensioning means.
10. In a car dumper, the combination of a car-receiving cradle mounted to rotate about a longitudinal axis within the car-receiving space; cradle-rotating means; and car clamping instrumentalities including a clamp and two cables both of which act to urge said clamp onto the car.
15. In a car dumper, the combination of a car-receiving cradle mounted to rotate about a longitudinal axis within the car-receiving space; cradle-rotating means; and car clamping instrumentalities including a car clamp, and two cables one of which lowers and raises said car clamp; and both of which urge said car clamp onto the car.
20. In a car dumper, the combination of a car-receiving cradle mounted to rotate about a longitudinal axis within the car-receiving space; cradle-rotating means; and car clamping instrumentalities including a car clamp, and two cables one of which lowers and raises said car clamp, and both of which cooperate with each other and with said cradle-rotating means to utilize rotation of said cradle to cause said cables to urge said car clamp onto the car in place.
25. In a car dumper, the combination of a car-receiving cradle mounted to rotate about a longitudinal axis within the car-receiving space; cradle-rotating means; and car clamping instrumentalities including two cables, one of which is power-operated and
30. In a car dumper, the combination of a car-receiving cradle mounted to rotate about a longitudinal axis within the car-receiving space; cradle-rotating means; and car clamping instrumentalities including a car clamp and has its other end power-operated, the other of which is weight-controlled, and both of which cooperate to clamp the car in place.
35. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
40. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which at least partially encompasses the car-receiving space and is weight-controlled, and both of which cables cooperate to cause said car clamp to clamp the car in place.
45. In a car dumper, the combination of a car-receiving cradle mounted to rotate about a longitudinal axis within the car-receiving space; cradle-rotating means; and car clamping instrumentalities including two cables, one of which is connected to said clamp and is power-operated, the other of which extends down one side, thence beneath and thence up the other side of the car-receiving space and is weight-controlled and both of which cables cooperate to clamp the car in place.
50. In a car dumper, the combination of a car-receiving cradle mounted to rotate about a longitudinal axis within the car-receiving space; cradle-rotating means; and car clamping instrumentalities including two cables, one of which is connected to said clamp, is power-operated and provided with tensioning means, the other of which extends down one side, thence beneath and thence up the other side of the car-receiving space, and both of which cables cooperate to clamp the car in place.
55. In a car dumper, the combination of a car-receiving cradle mounted to rotate about a longitudinal axis within the car-receiving space; cradle-rotating means; and car clamping instrumentalities including two cables, one of which is connected to said clamp and lowers the same toward the car, the other of which extends down one side, thence beneath and thence up the other side of the car-receiving space, and both of which cables cooperate with each other in the operation of said clamp; and cradle-rotating means to rotate said cradle to cause said other cable to be wrapped across said clamp and to urge the same toward the car.
60. In a car dumper, the combination of a car-receiving cradle mounted to rotate about a longitudinal axis within the car-receiving space; cradle-rotating means; and car clamping instrumentalities including two cables, one of which is power-operated and
65. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to clamp the car in place.
70. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
75. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
80. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
85. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
90. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
95. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
100. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
105. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
110. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
115. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
120. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
125. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.
130. In a car dumper, the combination of a car-receiving cradle mounted to rotate about a longitudinal axis within the car-receiving space; cradle-rotating means; and car clamping instrumentalities including two cables, one of which is secured at one end to said clamp and has its other end power-operated, the other of which is weight-controlled, and both of which cooperate to cause said car clamp to clamp the car in place.

- a car-receiving cradle mounted to rotate about a longitudinal axis within the car-receiving space; cradle rotating means; car clamping means including a clamp and a 5 clamp-lifting cable; means connecting and coordinating the operations of said cradle rotating means and said car clamping means to cause rotation of said cradle from its normal position to be accompanied by engagement of said car clamping means with the car; a car clamping cable; and means to cause said car clamping cable and said clamp-lifting cable to hold said car clamp in engagement with said car.
- 10 15. 12. In a car dumper, the combination of a car-receiving cradle mounted to rotate about a longitudinal axis within the car-receiving space; cradle-rotating means including a cradle-rotating cable and a cradle-rotating cable winding drum; car-clamping means including a car clamp, a car-clamp lifting cable and an operating cable drum; means connecting and coordinating the operations of said drums to cause rotation of said cradle from its normal position to be accompanied by engagement of said car-clamping means with said car; a car-clamping cable; and means to cause said car-clamping cable and said clamp-lifting cable to hold said car-clamp in engagement with said car.
- 20 25. 13. In a car dumper, the combination of a car track; a track carrying cradle mounted to rotate about a longitudinal axis within the car-receiving space; cradle rotating means; a car clamp; a car clamp lifting cable; a car clamp lifting cable winding drum; means connecting and coordinating the operations of said cradle rotating means with said drum to cause rotation of said cradle from its normal position to be accompanied by engagement of said clamp with the car; a car clamping cable; and means to cause said car clamping cable and said clamp-lifting cable to hold said clamp in engagement with the car.
- 30 35. 14. In a car dumper, the combination of a car-receiving and dumping cradle, and car clamping instrumentalities comprising clamping means, a controlling cable for said clamping means, a tensioning weight for said cable, and a stop which limits the ascent of said weight and causes said clamping means to release the car.
- 40 45. 15. In a car dumper, the combination of a car-receiving and dumping cradle, cradle inverting means including a cable, car clamping instrumentalities comprising clamping means, a controlling cable for said clamping means, and means for causing a differential action between said cables.
- 50 55. 16. In a car dumper, the combination of a car-receiving and dumping cradle, cradle inverting means including a cable, car clamping instrumentalities comprising clamping means, a controlling cable for said clamping means, and tensioning means for such cable.
- 60 65. means, a controlling cable for said clamping means, a tensioning weight for the last-mentioned cable, a stop which limits the ascent of said weight and causes said clamping means to release the car, and means for causing a differential action between said cables.
- 70 75. 17. In a car dumper, the combination of a car-receiving cradle mounted to rotate about a longitudinal axis within the car-receiving space, and car-clamping means including a clamp-setting cable having a bight about the car-receiving space.
- 80 85. 18. In a car dumper, the combination of a car-receiving cradle mounted to rotate about a longitudinal axis within the car-receiving space, and car-clamping means including a clamp above the car-receiving space, and a clamp-setting rope extending from said clamp in a downward direction on one side of the car-receiving space, thence beneath and across the car-receiving space, and thence in an upward direction on the other side of the car-receiving space.
- 90 95. 19. In a car dumper, the combination of a car-receiving cradle mounted to rotate about a longitudinal axis within the car-receiving space, and car-clamping means including a clamp above the car-receiving space, and a clamp-setting rope extending from said clamp in a downward direction on one side of the car-receiving space, thence between and across the car-receiving space, thence in an upward direction on the other side of the car-receiving space, and thence in a downward direction, and a weight attached to the last-mentioned portion of said cable.
- 100 105. 20. In a car dumper, the combination of a car-receiving cradle mounted to rotate about a longitudinal axis within the car-receiving space, and car-clamping means including a clamp-setting cable having a bight about the car-receiving space, a clamp attached to one end of said cable and a weight attached to the other end of said cable.
- 110 115. 21. In a car dumper, the combination of a car-receiving cradle mounted to rotate about a longitudinal axis within the car-receiving space, and car-clamping means including sheave wheels carried by said cradle below the car-receiving space, a sheave wheel extraneous to said cradle, a clamp above the car-receiving space, and a clamp-setting cable attached to said clamp and extending over said sheave-wheels in succession in the order named.
- 120 125. 22. In a car dumper, the combination of a car-receiving cradle mounted to rotate about a longitudinal axis within the car-receiving space; cradle rotating means; and car-clamping instrumentalities including two cables which cooperate to clamp the car in place, a motor for operating one of said cables, and tensioning means for such cable.

23. In a car dumper, the combination of a car-receiving cradle mounted to rotate about a longitudinal axis within the car-receiving space; cradle-rotating means; and car-clamping instrumentalities including a car clamp, two cables one of which lifts said car clamp and both of which cooperate to cause said car-clamp to clamp the car in place, a drum on which said car clamp lift-

ing cable is wound, a motor for rotating said drum, and a weight supported by one end of the other cable and constantly tensioning the latter.

In testimony whereof, we have signed our names to this specification.

SETH F. KNIGHT.
ALMON E. NORRIS.
